tion of New York

Application November 19, 1954, Serial No. 469,935

9 Claims. (Cl. 34—51)

This invention relates to methods and apparatus for drying web material and the like, and, more particularly, is concerned with improved means and methods for drying printing, coatings or the like, on endless, continuously moving web material, or in drying the web material itself.

Heretofore, various drying mechanisms have been provided for drying web material, or printing or coatings thereon, and such known mechanisms usually employ means for heating air followed by passage of the hot air over the web material to be dried. Mechanisms of this type are comparatively inefficient, involve the heating of large volumes of air, and with particularly poor heat transfer characteristics existing between the hot air and the web material to be dried. Other known drying mechanisms may possess objections due to the presence of too high a percentage of explosive solvent in the drier discharge, may be objectionable because of high horsepower requirements on blowers for moving the air through the drier, may have difficulties in establishing proper temperature conditions upon the web material being treated, the temperatures being so high that the web material may soften and rupture, or being so low that the web material or the solvent present in any printing or coating is not properly vaporized, or may have difficulties of threading the web material through the apparatus or in providing for the passage of knots therethrough.

It is the general object of my invention to avoid and overcome the foregoing and other difficulties of and objections to known drying mechanisms for web material, and particularly printed or coated web material, by the provision of improved methods and apparatus for rapidly drying web material, and specifically printed or coated web material, the method and apparatus functioning with a minimum of attention, cost and horsepower, with no danger of rupture to the web material, and with the apparatus being rapidly threaded, and allowing the passage of knots.

Another object of my invention is to provide methods and apparatus for drying printed webs and in which the web itself is heated and the air is not, and with a plurality of throats being established through which the air is moved at high velocity adjacent the surface of the web material having the printing or coating thereon, and followed by sharply divergent portions in which the air speed rapidly drops and the air flow is made turbulent.

Another object of my invention is the provision of methods and apparatus for drying web material in which the drying characteristics of the air are enhanced by maintaining its density high and its viscosity low, which follows when the air is not heated, and with the heat in the process and apparatus being concentrated upon the solvent to be removed to effect the vaporization thereon.

Another object of my invention is to provide methods and apparatus of the character described wherein the fan means for moving air through the drier is provided with a discharge nozzle having divergent sides positioned at angles not more than 3° so as to avoid too rapid a decel-

2

eration of the air and to thereby reduce the horsepower requirements of the fan means.

Another object of my invention is to provide drying apparatus operating with air under less than atmospheric pressure whereby dangers of leakage of air and solvent, as present in systems utilizing air under greater than atmospheric pressure, are substantially eliminated.

Another object of my invention is the provision of methods and apparatus of the type described wherein the amount of air moved through the apparatus is carefully coordinated with the amount of solvent removed and the explosive characteristics thereof so that the solvent in the discharged air never exceeds 50% of the lower explosive limit.

Another object of my invention is to provide improved heating means for progressively heating the film or web material, the heating means employing condensed steam, usually at less than atmospheric pressure, to provide substantially constant temperatures below the boiling point of water, which temperatures are required for certain film material, such as polyvinyl chloride.

Another object of my invention is to provide in apparatus such as set forth above movable covers for the drying tunnel and in the region of the high velocity throats, which movable covers facilitate threading of the web material through the apparatus, or which allow for the passage of splices or knots, and with the movable covers, in one form of my invention, comprising a flexible diaphragm which automatically adjusts itself under the differential pressures inside and outside of the tunnel to provide a throat passage of efficient dimension.

Another object of my invention is to provide apparatus of the type described wherein sealing means are positioned between the tunnel and the web material in the region of the introduction of the web material to the tunnel to reduce the flow of air around the web material and into the tunnel.

The foregoing object of my invention, and other objects which will become apparent as the description proceeds, are achieved by the provision of apparatus for drying printing and the like on endless, continuously moving web material including a tunnel member having an inside width substantially equal to the width of the web, means for directing the web into the tunnel near one end thereof, means adjacent the region of introduction of the web into the tunnel and inside of the tunnel to heat the web, means for directing the web through the tunnel, said means being positioned so that the web forms with one side of the tunnel and at longitudinally spaced points a plurality of narrow throats, each throat having on its upstream side gradually converging sides forming a nozzle to give relatively high throat velocities to any air passing the throat, and on its downstream side having relatively sharply diverging sides to create turbulence of the air after passing the throat, and fan means for drawing the air by suction through the tunnel in a direction opposite to the travel of the web. The amount of air passed through the tunnel is such that the air never contains more solvent than 50% of the lower explosive limit, and usually the fan means is provided with a discharge diffuser on the exhaust side of the fan which diffuser has side angles not exceeding 3°. The web is usually heated by roller means engaging the unprinted or uncoated side of the web, and with the roller means being heated by condensed steam at less than atmospheric pressure.

The height of the tunnel means is less than the width of the web material, and it usually is considerably less, and means are provided for reducing substantially to a minimum the flow of air around the web in the region of the introduction of the web to the tunnel. Also, movable cover means are usually provided on the tunnel in the region of each throat.

In accord with the method of the invention the web material to be dried is continuously moved in a path, the web is heated, at spaced points along the path cool air is directed with high velocity over the surface of the web, followed by a rapid drop in the velocity of the air causing turbulent mixing movement of the air and solvent to thereby effect the drying of the web or the drying of printing or the like thereon.

For a better understanding of my invention reference should be had to the accompanying drawings wherein Figs. 1A, 1B, and 1C constitute together a side elevation, partially broken away in section, of one typical apparatus embodiment of my invention;

Fig. 2 is a plan view of one end of the apparatus of Figs. 1A, 1B, and 1C, taken substantially in the region of line 2—2;

Fig. 3 is a horizontal cross sectional view taken substantially on line 3—3 of Fig. 1A;

Fig. 4 is a plan view of a modification of the movable closure adjacent the throat of the tunnel; and

Fig. 5 is an enlarged cross sectional view taken substantially on line 5—5 of Fig. 4.

Having reference to the drawings, and particularly to Figs. 1A, 1B, 1C and 2, the numeral 10 indicates generally a tunnel, usually constructed of sheet metal or similar material, and which does not have to be insulated, inasmuch as the air passing therethrough is not heated. The tunnel 10 is relatively long, for example, in one embodiment having a length of forty feet, is relatively shallow in vertical direction, for example, in one embodiment being 8 inches high, and is of a width to receive the widest web material to be dried, for example, in one embodiment being approximately 56 inches wide. In order to maintain the air velocities throughout the tunnel, such as hereinafter described, it is preferable, in order to achieve highest efficiencies, that the web material W being dried in the tunnel be substantially the full width of the inside of the tunnel. However, web material of materially less width than that of the tunnel can be successfully dried but with lower efficiencies.

The tunnel 10 is mounted in any suitable manner and in any convenient position in the factory in which the drying operation is to be performed, it being remembered that the tunnel should be positioned so as to facilitate threading of the web material W therethrough. Suitable frame means 12 are indicated in the drawing for supporting the tunnel in a typical installation.

Near one end of the tunnel 10, as shown in Fig. 1A, the web material W is adapted to be introduced and this is preferably achieved by introducing the web material from beneath the tunnel, the web material W passing over a bar 14 having a flat arcuate curve over its length, and with the bar 14 engaging with the side of the web material W opposite to the printing or coating thereon. The function of the bar 14 is to smooth the web material laterally to remove wrinkles or waves, and with the web material after leaving the bar 14 passing through a curved opening 16 in a pan-shaped housing 18 extending laterally of and secured to the underside of the tunnel 10.

The curved opening 16 in the housing 18 is defined on one side, namely the left side in Fig. 1A, by the housing itself, and at the other side by a door 20 hinged at 22 to a plate 24. The plate 24 has longitudinally extending slots therein through which extend bolts 26 fastened to the housing 18 so that the position of the plate 24 and the clearance between the edge of the door 20 and the side of the web material W can be adjusted so as to maintain the opening 16 with the smallest possible clearances, but without the web material W touching either the housing 18 or the door 20. The bar 14 is mounted to be adjustably rotated about its axis to bring the flat curve of the web W into close proximity to the sides of the opening 16. By maintaining these clearances,

small the loss of air through the opening 16 is maintained to a minimum.

A spring 28 fastened at one end of the door 20 and to its opposite end at a bracket 30 resiliently holds the door 20 in the position illustrated but allows the door to yield against the action of the spring 28 should a knot or heavy splice occur in the web material during its passage into the tunnel 10.

Positioned in the housing 18 and extending also through an opening in the bottom of the tunnel 10 is a hollow heating drum 34 which is journaled at its ends on suitable bearing plates 36 carried by the ends of the housing 18, and with the drum being of a length equal to the inside width of the tunnel. A flexible strip of nylon or other suitable material, and indicated by the numeral 38, is secured to the bottom of the tunnel 10 adjacent one edge of the drum 34 and in a position to wipe on the surface of the drum so as to effectively seal off the passage of air between the drum and the bottom of the tunnel. A door 40 hinged at 41 to a plate 42 is mounted at the other side of the drum 34 on the bottom of the tunnel 10, and in a position to just clear the surface of the web material bearing the printing or coating, and again for the purpose of sealing off, as far as possible, the flow of air between the drum 34 and the tunnel 10. Bolts 43, received in arcuate slots adjustably mount the plate 42 on the tunnel and a spring 44 normally holds the door 40 in sealing position but allows the door to swing for the passage of knots or other heavy splices in the web material W.

An important part of the invention is the heating of drum 34, by condensing steam passed to the interior of the drum through its journals. The arrangement is such that the steam condenses inside of the drum 34 so as to create therein pressures of less than atmospheric and with the temperature of the drum being maintained at not higher than 190° F. for polyvinyl chloride film, for example. The condensed steam is removed in known manner from the interior of the drum 34, and additional steam is supplied to the drum by temperature responsive means, and the result is that very constant and uniform temperatures can be maintained inside of the drum 34 in the manner described and because of the condensing steam action at temperatures below normal steam temperatures, and without going to the considerably greater expense of electric heating.

The web material W in passing over the drum 34 through the arcuate contact illustrated in Fig. 1A is strongly heated by means of the drum so that the temperature of the web material itself is raised substantially to the temperature of the roller, for example, to 190° F. for polyvinyl chloride film material, this being substantially the upper temperature limit beyond which the unsupported film may soften and become distorted. The film is heated substantially uniformly throughout its entire thickness and the solvent material present in any printing ink or coating on the film is rendered volatile.

Leaving the drum 34 the web material W passes through the tunnel 10 towards the opposite end thereof, and in this passage is so positioned as to provide a plurality of areas producing relatively narrow throats and alternate areas of relatively sharp diffusion. More specifically, and having particular reference to Figs. 1A, 1B and 1C, the web material leaving the heating drum 34, passes to roller 44 journaled between the sides of the tunnel 10 and positioned so as to carry the web material W relatively close to the inside of the top of the tunnel. Note that the roller 44 is positioned relatively close to the heating drum 34 so that the path of the web material W climbs rather sharply between the heating drum 34 and the roller 44. However, the web material leaving the roller 44 extends in a rather flat angle down and around roller 46 positioned at some distance from roller 44 so that between rollers 46 and 44 the web material together with the inside of the top of the tunnel provides a gradu-

ally diverging passage or throat. Or stated conversely, and as hereinafter explained in relation to the airflow, a diverging passage is provided terminating in the relatively narrow throat provided between the top of the web material immediately above the roller 44 and the inside of the top of the tunnel 10. A hinged cover 48 is provided on the top of the tunnel 10 above the roller 44, the cover 48 yielding about its hinge point 50 to allow the passage of knots or heavy splices in the web material lengthwise of the tunnel, but normally forming a sealed closure for the top of the tunnel 10.

Leaving the roller 46 the web material W rises on a relatively sharp angle to pass over roller 52 positioned, like roller 44, near the top of the tunnel, and with the web material W then extending at a relatively long flat angle to pass beneath roller 54. Thence the web material rises sharply to pass over roller 56 and then at a long flat angle to pass under roller 58, again rising sharply to pass over roller 60 and thence out of the tunnel by way of a bottom opening 62 near the other end of the tunnel, a roller 64 being provided in association with the opening 62 to facilitate removal of the web material from the tunnel.

From the foregoing description it will be evident that during the passage of the web material W lengthwise of the tunnel in the manner described that a plurality of relatively narrow throats are provided in the region of rollers 44, 52, 56 and 60, these throats being defined by the gradually narrowing distance between the web material and the inside of the upper portion of the tunnel, each throat being followed by relatively rapidly diverging diffusion areas formed between the web material W and the top of the tunnel. Each of the rollers 52, 56 and 60 is provided with an associated hinged cover or door 66, 68 and 70 similar to the door 48 and for purposes previously described. All of the doors 48, 66, 68 and 70 are of low mass and serve as means to blow open to minimize damage due to explosion, which might occur because of power failure or other shutdown in case of an air raid, for example. Incidentally, my improved apparatus is particularly explosion proof being a suction system and can normally be started up without danger even though the line has been stopped for some reason.

At the end of the tunnel 10 near which the web material W is introduced a blower 71 is provided upon the frame 12 for pulling air through the tunnel 10. Fig. 1A and Fig. 2 illustrate that the blower 71 is connected by a funnel-shaped housing 72 with the end of the tunnel 10, the blower 71 being driven, for example, by belt 74 from a suitable prime mover. A flexible connection 73 is usually provided between the blower 71 and the housing 72 to reduce vibration. The discharge side of the blower 71 is provided with a discharge diffuser 76 which is formed so that its side diverges at no greater than an angle of 3°, and this notably minimizes the overall horsepower required for the operation of the blower 71, and also notably reduces the noise level of the exhaust system.

With the blower 71 in operation air is drawn in through the remote end of the tunnel in the manner shown by the arrows in Fig. 1C, and this air passing through the throat formed by the roller 60 is given a relatively high velocity during its movement through the throat but immediately after passing the throat the sharply diverging area between the web material and the inside of the top of the tunnel causes the air velocity to drop off sharply and induces turbulent mixing of the air and solvent from the printing or coating on the web material. This same action of inducing high velocity travel of the drying air through a throat followed by a zone of turbulence and diffusion is periodically repeated throughout the passage of the air through the tunnel, the throats being provided by the rollers 56, 52 and 44 in turn during the travel of the air, each period of high velocity air travel being followed by an interposed slowdown of the air travel plus turbulence and diffusion whereby a very effective removal of the

solvent from the printing, and/or drying of the web material W, is effected.

It should be noted here that the several throats provided along the tunnel in the manner described are arranged to have substantially the same pressure drop. This means that the throat at roller 60 is slightly larger than the throat at roller 56, which is slightly larger than the throat at roller 52, which in turn is slightly larger than the throat at roller 44.

In previously known driers there has always tended to be a concentration of vapor or solvent at the surface of the film being dried which blankets the solvent within the boundary layer and inhibits proper drying or evaporating and removal of the solvent. Any such action in the present drier is eliminated due to the boundary layer removing action of the several throats and subsequent diffusion areas in the manner described.

The drier of the present invention differs basically from most driers in that only the film and/or ink or coating thereon are heated, and the air is not. The advantage of this is that the drying characteristics of the air are enhanced by maintaining the density of the air high and its viscosity low, and this follows when the air is not heated. The vaporization of a solvent in the ink or coating is promoted because the temperature of the solvent is maintained at a high level. In fact it has been found that once the film is heated by the drum 34 the film cools down very slowly during its travel through the tunnel. This is because convective heat transfer from the film to the air is relatively poor. The amount of heat necessary to effect the drying action in the present application is far less than that required in conventional apparatus so that the cost of operation is notably reduced, and the disadvantages of discharging large amounts of hot air are eliminated.

The tunnel 10 is preferably provided with baffle means to assist in obtaining the alternate throat and diffusion regions as previously described even though the width of the web W should be considerably less than the width of the tunnel 10. Specifically, baffles 90 are provided for this purpose which extend the full width of the tunnel 10 adjacent each of rollers 44, 52, 56 and 60 and as shown in Figs. 1A, 1B and 1C.

Instead of providing the doors 48, 66, 68 and 70 in the manner heretofore described, it is sometimes advantageous to employ a flexible and resilient diaphragm instead. Figs. 4 and 5 illustrate such a diaphragm, the diaphragm, for example of rubber sheeting, being indicated by the numeral 80 and being sealed in a frame 82 hinged at 84 to the top of the tunnel 10. The frame 82 drops down to make sealing contact with the top of the tunnel, but can be lifted to facilitate threading of the tunnel with the web material W. The advantage of the diaphragm 80 over the rigid doors heretofore described is that during the flow of air at high velocity through the throats of the tunnel the diaphragms 80 can adjust themselves in relation to the spacing from the web material to give the proper relation between air velocity and pressure drop in the region of each throat.

From the foregoing it will be recognized that the various objects of the invention have been achieved by the provision of relatively simple, highly efficient and yet relatively inexpensive to operate drying apparatus. The amount of air drawn through the tunnel is controlled so that at no time does the air discharge from the blower 71 contain more than 50% of the lower explosive limit of any volatile solvent present in either the film, printing ink or coating on the film. It has been found that in the treatment of printed polyvinyl chloride films, and with apparatus built substantially in the size heretofore described, that a very excellent drying action is achieved, with no solvent being determinable in the tunnel in the region of the last diffusion area, and with the film leaving the drying tunnel at temperatures in the region of

150-160° F., and with the film being capable of being directly wound upon itself without smearing of the ink.

While in accord with the patent statutes certain best known embodiments of the invention have been illustrated and described in detail, it is to be particularly understood that the invention is not to be limited thereto or thereby, but that the scope of the invention is defined in the appended claims.

What I claim is:

1. Apparatus for drying printing and the like on endless, continuously moving web material including a tunnel member having an inside width substantially equal to the width of the web and a height less than the width of the web, means for directing the web into the tunnel near one end thereof, means for reducing substantially to a minimum the flow of air around the web in the region of the introduction of the web to the tunnel, hollow drum means adjacent the region of introduction of the web to the tunnel and inside the tunnel and progressively engaging with the unprinted side of the web to heat the web, means for heating the drum with condensed steam and at less than atmospheric pressure, roller means for directing the web through the tunnel, said roller means being positioned so that the web forms with one side of the tunnel a plurality of narrow throats each throat having on its upstream side gradually converging sides forming a nozzle to give relatively high throat velocities to any air passing the throat, and on its downstream side having relatively sharply diverging sides to create turbulence of the air after passing the throat, fan means for drawing air through the tunnel in a direction opposite to the travel of the web and in a volume so that the air never contains more solvent than 50% of the lower explosive limit, a discharge diffuser on the exhaust side of the fan means having side angles not exceeding 3° to reduce the horsepower requirements of the fan means, and movable cover means on the tunnel in the region of each throat.

2. Apparatus for drying printing and the like on endless, continuously moving web material including a tunnel member having an inside width substantially equal to the width of the web and a height less than the width of the web, means for directing the web into the tunnel near one end thereof, means for reducing substantially to a minimum the flow of air around the web in the region of the introduction of the web to the tunnel, hollow drum means adjacent the region of introduction of the web to the tunnel and inside the tunnel and progressively engaging with the unprinted side of the web to heat the web, means for heating the drum with condensed steam and at less than atmospheric pressure, roller means for directing the web through the tunnel, said roller means being positioned so that the web forms with one side of the tunnel a plurality of narrow throats each throat having on its upstream side gradually converging sides forming a nozzle to give relatively high throat velocities to any air passing the throat, and on its downstream side having relatively sharply diverging sides to create turbulence of the air after passing the throat, fan means for drawing air through the tunnel in a direction opposite to the travel of the web and in a volume so that the air never contains more solvent than 50% of the lower explosive limit, and a discharge diffuser on the exhaust side of the fan means having side angles not exceeding 3° to reduce the horsepower requirements of the fan means.

3. Apparatus for drying printing and the like on endless, continuously moving web material including a tunnel member having an inside width substantially equal to the width of the web and a height less than the width of the web, means for directing the web into the tunnel near one end thereof, means for reducing substantially to a minimum the flow of air around the web in the region of the introduction of the web to the tunnel, hollow drum means adjacent the region of introduction of the web to the tunnel and inside the tunnel and progressively engaging with the unprinted side of the web to heat the web, means for heating the drum with condensed steam and at less than atmospheric pressure, roller means for directing the web through the tunnel, said roller means being positioned so that the web forms with one side of the tunnel a plurality of narrow throats each throat having on its upstream side gradually converging sides forming a nozzle to give relatively high throat velocities to any air passing the throat, and on its downstream side having relatively sharply diverging sides to create turbulence of the air after passing the throat, fan means for drawing air through the tunnel in a direction opposite to the travel of the web and in a volume so that the air never contains more solvent than 50% of the lower explosive limit, and a discharge diffuser on the exhaust side of the fan means having side angles not exceeding 3° to reduce the horsepower requirements of the fan means.

the web to the tunnel and inside the tunnel and progressively engaging with the unprinted side of the web to heat the web, means for heating the drum with condensed steam and at less than atmospheric pressure, roller means for directing the web through the tunnel, said roller means being positioned so that the web forms with one side of the tunnel a plurality of narrow throats each throat having on its upstream side gradually converging sides forming a nozzle to give relatively high throat velocities to any air passing the throat, and on its downstream side having relatively sharply diverging sides to create turbulence of the air after passing the throat, and fan means for drawing air through the tunnel.

4. Apparatus for drying printing and the like on endless, continuously moving web material including a tunnel member having an inside width substantially equal to the width of the web and a height less than the width of the web, means for directing the web into the tunnel near one end thereof, means for reducing substantially to a minimum the flow of air around the web in the region of the introduction of the web to the tunnel, hollow drum means adjacent the region of introduction of the web to the tunnel and inside the tunnel and progressively engaging with the unprinted side of the web to heat the web, roller means for directing the web through the tunnel, said roller means being positioned so that the web forms with one side of the tunnel a plurality of narrow throats each throat having on its upstream side gradually converging sides forming a nozzle to give relatively high throat velocities to any air passing the throat, and on its downstream side having relatively sharply diverging sides to create turbulence of the air after passing the throat, fan means for drawing air through the tunnel in a direction opposite to the travel of the web and in a volume so that the air never contains more solvent than 50% of the lower explosive limit, a discharge diffuser on the exhaust side of the fan means having side angles not exceeding 3° to reduce the horsepower requirements of the fan means, and movable cover means on the tunnel in the region of each throat.

5. Apparatus for drying a continuously moving web of sheet material, said apparatus comprising a tunnel, means for directing a web progressively into one end of the tunnel, means at said end of the tunnel for progressively heating the web, a series of rollers located entirely within the tunnel to direct the web along the tunnel said rollers being positioned alternately near opposite walls of the tunnel to direct the web in a sinuous path with a wall of said tunnel and said web providing therebetween a series of narrow throats, each throat having at its upstream reach gradually converging sides forming a nozzle to provide high velocities to air passing the throat and at its downstream reach sharply diverging sides to create turbulence of air passing said throat, means providing a flow of air along said tunnel in a direction opposite to the direction of travel of the web, openings in at least one wall of said tunnel adjacent the narrow throats provided by close proximity of some of said rollers and said last-named wall, and covers over said openings for closing them, said covers being displaceable outwardly of said tunnel to permit passage of knots or splices and under excess pressure in said tunnel.

6. Apparatus for drying a continuously moving web of sheet material said apparatus comprising a tunnel, means for directing a web progressively into one end of the tunnel, means at said end of the tunnel for progressively heating the web, a series of rollers located entirely within the tunnel to direct the web along the tunnel said rollers being positioned alternately near opposite walls of the tunnel to direct the web in a sinuous path with a wall of said tunnel and said web providing therebetween a series of narrow throats, each throat having at its upstream reach gradually converging sides forming a nozzle to provide high velocities to air passing the throat and at its downstream reach sharply diverging sides to create turbulence of air passing said throat, means providing a flow of air along said tunnel in a direction opposite to the direction of travel of the web, openings in at least one wall of said tunnel adjacent the narrow throats provided by close proximity of some of said rollers and said last-named wall and covers over said openings for clos-

ing them, said covers being displaceable outwardly of said tunnel to permit passage of knots or splices and under excess pressure in said tunnel, said covers each comprising a frame supporting a flexible diaphragm providing a displaceable wall portion of the tunnel at one of the throats.

7. Apparatus for drying a continuously moving web of sheet material said apparatus comprising a tunnel means for directing a web progressively into one end of the tunnel, means at said end of the tunnel for progressively heating the web, a series of rollers located 15 entirely within the tunnel to direct the web along the tunnel said rollers being positioned alternately near opposite walls of the tunnel to direct the web in a sinuous path with a wall of said tunnel and said web providing therebetween a series of narrow throats, each throat having at its upstream reach gradually converging sides forming a nozzle to provide high velocities to air passing the throat and at its downstream reach sharply diverging sides to create turbulence of air passing said throat, means providing a flow of air along said tunnel in a direction opposite to the direction of travel of the web, openings in at least one wall of said tunnel adjacent the narrow throats provided by close proximity of some of said rollers and said last-named wall, and covers over said openings for closing them, said covers being displaceable outwardly of said tunnel to permit passage of knots or splices and under excess pressure in said tunnel, said covers each comprising a frame supporting a flexible diaphragm providing a displaceable wall portion of the tunnel at one of the throats, said frame being hingedly secured to said tunnel wall at one of said wall openings.

8. Apparatus for drying a continuously moving web of sheet material, said apparatus comprising a tunnel means for directing a web progressively into one end of the tunnel, means at said end of the tunnel for progressively heating the web, a series of rollers having faces extending within the tunnel entirely across the width of the web to direct the web along the tunnel, said rollers being positioned alternately near opposite walls of the tunnel to direct the web in a sinuous path with a wall of said tunnel and said web providing therebetween a series of narrow throats, each throat having at its upstream reach gradually converging sides forming a nozzle to provide high velocities to air passing the throat and at its downstream reach sharply diverging sides to create turbulence of air passing said throat, means providing a

flow of air along said tunnel along the web, openings in at least one wall of said tunnel adjacent the narrow throats provided by close proximity of some of said rollers and said last-named wall, and covers over said openings for closing them, said covers being displaceable outwardly of said tunnel to permit passage of knots or splices and under excess pressure in said tunnel, said covers each comprising a flexible diaphragm providing a flexible wall portion of a throat of said tunnel opposite a face of one of said rollers and adapted to assume under a balance of elastic membrane and aerodynamic forces a position defining a stable minimum throat gap, said covers being hingedly secured to said tunnel wall at one of said wall openings.

9. Apparatus for drying printing and the like on endless, continuously moving web material including a tunnel member having an inside width substantially equal to the width of the web and a height less than the width of the web, means for directing the web into the tunnel near one end thereof, means for reducing substantially to a minimum the flow of air around the web in the region of the introduction of the web to the tunnel, means adjacent the region of introduction of the web to the tunnel and inside the tunnel and progressively engaging with the unprinted side of the web to heat the web, roller means for directing the web through the tunnel, said roller means being positioned so that the web forms with one side of the tunnel a plurality of narrow throats each throat having on its upstream side gradually converging sides forming a nozzle to give relatively high throat velocities to any air passing the throat, and on its downstream side having relatively sharply diverging sides to create turbulence of the air after passing the throat, and fan means for drawing air through the tunnel.
